UNITED STATES PATENT OFFICE.

ALESSANDRO GIOYER, OF BELLINZONA, SWITZERLAND.

ADJUSTABLE WRENCH.

1,102,040.

Specification of Letters Patent. Patented June 30, 1914.

Application filed January 13, 1913. Serial No. 741,663.

To all whom it may concern:

Be it known that I, ALESSANDRO GIOYER, subject of the King of Italy, resident of San Giovanni Via della Caserma, Bellinzona, Switzerland, have invented new and useful Improvements in Adjustable Wrenches, of which the following is a specification.

The object of the present invention is an adjustable wrench.

10 In the annexed drawing a constructional form is shown by way of example.

Figures 1 and 2 are two views of said wrench. Figs. 3 and 4 show the same partially dismounted, and Figs. 5 to 9 show 15 some details.

The wrench is made of six principal pieces, namely of a handle —*a*—, two jaws —*b*—*c*— which are capable of sliding in the recesses between the bifurcations of the 20 handle, and of three pins *b*₂ *c*₂ *e*. At one end the handle is forked, and each of the bifurcations is provided with a cam slot *a*₁, the said slots being arranged in polar symmetry on opposite sides of the pin *e*, passing 25 through the said bifurcations, and serving as guides in which the pins *b*₂ *c*₂ on the jaws *b* and *c*, respectively, may be caused to slide, the whole being protected by two round disks —*d*.

30 In the center of the faces of the fork is fitted the pin —*e*— around which the handle revolves. The slots *a*, are eccentric with regard to the said pivot —*e*.

The parts above described are assembled 35 to form the wrench by placing the jaws *b* and *c* together so that the portion *c*₃ of the jaw *c* is introduced into the socket *b*₃ of the jaw *b* and the slot *b*₁ and *c*₁ of the jaws *b* and *c* are brought into alinement. There- 40 upon the assembled jaws are introduced into the recess between the bifurcations of the forked handle *a*, whereupon the pins *b*₂ and *c*₂ are passed through the said bifurcations and the jaws, so that each pin engages one 45 of the cam slots *a*₁ *a*₂, respectively, and the pivot pin *e* is passed through corresponding openings in the said bifurcations and through the two slots *b*₁ and *c*₁, respectively, the pins are then secured against displacement 50 in any suitable or convenient manner. When the parts are so assembled the movement of the handle in the plane of the jaws

and with respect to them will cause the pins *b*₂ and *c*₂, and with them the said jaws, to approach or to recede from one another, according to the direction of said movement. Therefore, working the handle from right to left, and vice versa, the two jaws draw near or withdraw owing to the action of the eccentric slots *a*₁ and from this movement 60 one can obtain an opening between the jaws varying, for instance, from 10 to 30 millimeters.

To screw up a nut one will have to work the handle from right to left, and the unscrewing will be obtained by reversing the wrench.

The universal wrench hereinbefore described is extremely simple and affords a firm hold of the nut.

Having described my invention what I claim is:

1. In a wrench, a handle and a pivot pin arranged in the head of the same, and a pair of cams symmetrical with respect to the pivot pin, in combination with a pair of jaws provided with slots engaging the pivot pin of the handle, each jaw engaging one of the cams, respectively, of the handle.

2. In a wrench, a handle forked at its head, a pivot pin arranged in the said forked portion, and a pair of cams symmetrical with respect to the said pivot pin, in combination with a pair of jaws telescopically arranged with respect to each other, engaging the forked portion of the handle and each provided with a slot engaging the pivot pin of the handle, each jaw engaging one of the cams, respectively, of the handle.

3. In a wrench, a handle forked at its head, a pivot pin arranged in the said forked portion, and a pair of cam slots in the forked portion, in combination with a pair of jaws engaging the forked portion of the handle and each provided with a slot engaging the pivot pin of the handle, each jaw being provided with a pin engaging one of the cam slots, respectively, of the handle.

In testimony whereof I affix my signature in presence of two witnesses.

ALESSANDRO GIOYER.
